UNITED STATES PATENT OFFICE.

FREDERIC ALLEN, OF WORCESTER, MASSACHUSETTS.

MOP-HEAD.

Specification of Letters Patent No. 16,137, dated December 2, 1856.

To all whom it may concern:

Be it known that I, FREDERIC ALLEN, of Worcester, in the county of Worcester and State of Massachusetts, have invented a new 5 and useful Improvement in Mop-Heads, which I do hereby declare is fully described and represented in the following specification and the accompanying drawings, of which—

10 Figure 1, is a side view, and Fig. 2, an edge elevation of the said article.

In carrying out or constructing my invention I take a tapering bar A, of spring steel, and bend it at the middle, and from 15 thence to one end and at such end as shown at a, b, c, in Fig. 1. It thus has three bends or flexures the latter or that shown at c, being so as to form an eye d, for the reception of a link e, which has the bar inserted 20 through it previously to the formation of the eye. The other end of the bar A, I bend down so as to form a flat hook f, to hold the link in place when the hook or end of the bar A, is extended through it, as shown in 25 dotted lines in Fig. 1. The bar A, should be provided with a shank g, for connecting it with a mop handle B.

In applying the mop cloth to the aforesaid head it should be placed on it while the 30 link e, is off the hook f. This having been accomplished the head is to be compressed on the cloth and the link slipped on the hook. By this process the flexure b, of the spring will be not only operated so as to 35 confine the cloth in place, but it will give way in accordance with the thickness of the

cloth and adapt itself to the same. The said flexure thus renders the mop head self adjusting and applicable to receive either a thick or thin cloth. This fixture is not 40 found in the common bar clamp mop head operated by a screw. In my improved mop head the link is always in one position when the clamp contains a cloth, whatever may be the thickness of the cloth. No setting up 45 of a screw is required to fix the cloth to the head. Such being done by the self adapting spring flexure b, and the link while being bent down toward and conformed to the remainder of the mop head. 50

My improved mop head though simple in its construction is very advantageous in operation.

I do not claim a clamp formed of two bars hinged together at one end of each and 55 provided at their opposite ends with a screw for forcing one of them toward the other, but

What I do claim is—

My improved spring clamp mop head as 60 made of a bar of spring steel as stated bent and formed with an eye and a hook at its opposite ends as explained and having a link applied thereto so as to operate therewith as specified. 65

In testimony whereof I have hereunto set my signature this — day of August 1856.

FREDERIC ALLEN.
